J. E. Johnson.

UNITED STATES PATENT OFFICE.

JOE E. JOHNSON, OF WALDO, ARKANSAS.

JOURNAL-BOX.

SPECIFICATION forming part of Letters Patent No. 392,206, dated November 6, 1888.

Application filed June 19, 1888. Serial No. 277,530. (No model.)

To all whom it may concern:

Be it known that I, JOE E. JOHNSON, a citizen of the United States, residing at Waldo, in the county of Columbia and State of Arkansas, have invented new and useful Improvements in Journal-Boxes, of which the following is a specification.

My invention relates to improvements in journal-boxes, having for its object to provide a simple and effective means to adjust the bearing to compensate for wear; and it consists in a certain novel construction and arrangement, fully set forth hereinafter in connection with the accompanying drawings, wherein—

15 Figure 1 is a longitudinal sectional view of a journal-box embodying my improvements. Fig. 2 is a transverse sectional view thereof through one of the adjusting-blocks. Fig. 3 is a detail perspective view of one of the adjusting-blocks.

Referring to the drawings, this box is adapted to be employed in all kinds of machinery, either heavy or light, the object being to provide means whereby the wear may be taken up as it becomes apparent, the means being adapted to be nicely adjusted to take up all play without binding the spindle.

I am aware that it is not new to insert small wedges or blocks under the cap-plate of the box, and as the bearing wears reduce the thickness of the said block and thus permit the cap-plate to be lowered; but it will be seen that much difficulty is experienced in this manner of adjustment to reduce the thickness of the blocks exactly enough to properly adjust the bearing, and, further, much time is occupied in adjusting a bearing in this manner.

40 A designates the pillow-block of the improved box having the lower half of the bearing therein, and B designates the cap-plate, which is arranged above the pillow-block and is provided with the upper half of the bearing. The pillow-block and cap-plate are provided, respectively, with registering apertures 45 a b, the apertures a being tapped, as shown in the drawings.

The bolts C C are screwed at their lower ends into the tapped apertures in the pillow-block, and are provided with rigid (and preferably 50 integral) collars D D, to fit in sockets or de-

pressions E E around the upper ends of the tapped apertures.

F F represent adjusting-blocks having apertures f f therein, which register with the apertures a in the pillow-block and receive the 55 upper ends of the bolts C C, and the said blocks fit in transverse channels or grooves G G in the upper side of the pillow-block and bear on the upper sides of the collars D.

The apertures b in the cap-plate receive the 60 upper ends of the bolts, and the set-nuts H, which are screwed on the extremities of the bolts, bear on the upper side of the cap-plate and hold the latter firmly pressed on the adjusting-blocks. The upper ends of the bolts 65 are squared to receive a wrench or a key to enable the lower ends of the bolts to be screwed into the tapped apertures in the pillow-block.

The manner of connecting the parts of this journal-box will now be readily seen. The bolts 70 are screwed in the apertures in the pillow-block. The adjusting-blocks are arranged on the bolts above the collars, and after the spindle has been arranged in the bearing the cap-plate is arranged on the upper ends of the bolts 75 and allowed to bear on the upper sides of the adjusting-blocks. The bolts are now screwed up or down in the pillow-block until the cap-plate bears properly on the upper side of the spindle, after which the set-nuts are engaged 80 on the upper ends of the bolts and screwed down, so as to tightly clamp the cap-plate against the adjusting-blocks. As the bearing becomes worn, the cap-plate may be lowered by first disengaging the set-nuts and then 85 screwing the bolts down into the pillow-block.

It will be seen that the adjusting-blocks are employed to distribute the pressure of the collars on the under side of the cap-plate and thus support the cap-plate evenly. The adjusting-blocks are also employed to prevent a longitudinal movement of the cap-plate, as might be the result if the portions of the bolts between the pillow-block and the cap-plate were unsupported. It will be seen that the lower 95 sides of the said blocks fit snugly in the channels or grooves of the pillow-block and their upper sides are in contact with the lower side of the cap-plate. These adjusting-blocks may be formed integral with the cap-plate, if pre- 100

ferred; but I consider it advantageous to have them separate.

The adjusting device described is simple and effective, it consisting simply of vertically-adjustable bolts having rigid collars which support the cap-plate in any desired position, and the bearing is adjusted without removing any of the parts thereof with the exception of the clamping-nuts. Further, these set-nuts are to not liable to jar loose, as the elasticity of the metal collars and adjusting-blocks forms a lock which holds the said nuts firmly in position.

It will be observed that the adjusting device is entirely independent of the construction of the bearing, and by making the described apertures and channels or grooves it may be applied to any bearing now in use. Therefore I do not wish to limit myself to the peculiar construction of bearing herein shown.

Having thus described my invention, I claim—

1. In a journal-box, the bolts C, arranged at their lower ends in the pillow-block on opposite sides of the bearings and having rigid collars D thereon, in combination with the cap-plate mounted on the bolts and supported by the said collars, and the set-nuts engaging the upper ends of the bolts and bearing on the cap-plate, substantially as specified.

2. In a journal-box, the bolts arranged in tapped apertures in the pillow-block and having rigid collars, and the adjusting-blocks arranged on the bolts and bearing on the said collars, in combination with the cap-plate

bearing on the adjusting-blocks and the set-nuts engaging the upper extremities of the bolts, substantially as specified.

3. In a journal-box, the combination of the pillow-block A, having the tapped apertures a, the depressions or sockets E at the upper ends of the said apertures, and the transverse channels or grooves G, communicating with the said depressions or sockets, the bolts mounted in the tapped apertures and each having a squared upper end and a rigid collar arranged at an intermediate point and adapted to fit in the said depressions or sockets in the pillow-block, the adjusting-blocks having apertures receiving the bolts and bearing on the said collars thereon, said adjusting-blocks being adapted to fit snugly in the channels or grooves G, the cap-plate having smooth apertures b, registering with the apertures a in the pillow-block and receiving the upper ends of the said bolts, and the set-nuts engaging the upper projecting ends of the bolts and bearing on the upper side of the cap-plate to clamp the latter firmly against the adjusting-blocks, substantially as and for the purpose hereinbefore specified.

In testimony that I claim the foregoing as my own I have hereto affixed my signature in presence of two witnesses.

JOE E. JOHNSON.
